UNITED STATES PATENT OFFICE.

PHER EDWARD JOHNSON AND EDWARD ANDERSON, OF NEW YORK, N. Y.

EXTENSION-LADDER.

1,116,073.

Specification of Letters Patent.

Patented Nov. 3, 1914.

Application filed July 2, 1914. Serial No. 848,608.

To all whom it may concern:

Be it known that we, PHER EDWARD JOHNSON and EDWARD ANDERSON, both citizens of the United States, and residents of the city 5 of New York, borough of Brooklyn, in the county of Kings and State of New York, have invented a new and Improved Extension-Ladder, of which the following is a full, clear, and exact description.

10 The object of the invention is to provide a new and improved ladder capable of being extended in a very simple and secure manner.

In order to accomplish the desired result, 15 use is made of extension side pieces connected with each other by adjustable rungs or steps and adjustably secured to the main side pieces of the ladder.

A practical embodiment of the invention 20 is represented in the accompanying drawings forming a part of this specification, in which similar characters of reference indicate corresponding parts in all the views.

Figure 1 is a perspective view of a double 25 ladder provided with the extension device; Fig. 2 is an enlarged sectional plan view of part of the same on the line 2—2 of Fig. 1; Fig. 3 is a sectional side elevation of the same on the line 3—3 of Fig. 2; Fig. 4 is a 30 face view of one of the connecting parts of one of the clamps; and Fig. 5 is an enlarged sectional plan view of the extension device on the line 5—5 of Fig. 1.

The improvement is shown applied to a 35 double ladder, that is, one formed of two ladders A and B, connected with each other at their upper ends by hinges C so that one ladder forms a prop for the other when the ladders are in extended position. The 40 hinges C permit of folding the ladders one on top of the other when the double ladder is to be stored and not in use. As the extension device is the same for each ladder A and B it suffices to describe but one in detail, especially as the extension device may 45 be used on a single ladder.

The side pieces or rails D, D' of each ladder A and B are rigidly connected with each other by rungs E and onto the outer faces 50 of the said side pieces D, D' fit extension side pieces or rails F, F' fastened in position on the said main side pieces D, D' by clamps G, preferably two for each extension side piece F and F'. The clamp G is provided 55 with bars G', G² having angular members G³, G⁴ slidably fitting one on the other so as

to permit using the clamp G on side pieces D, F and D', F' of different width. The members G³ and G⁴ are slidably connected with each other by a rivet H having countersunk heads H', H², of which the latter slidingly fits into a groove in the member G³ and the shank H³ of the shaft H engages a slot in the member G³, as indicated in dotted lines in Fig. 2. The member G³ fits against 60 the inner face of the corresponding side piece D or D'. The bars G', G² extend across the front and rear of the side pieces D, F or D', F', and terminate in threaded rods G⁵ connected with each other by a bar 65 G⁶ forced against the outer face of the corresponding extension side piece F or F' by wing nuts G⁷ screwing on the threaded portions of the rods G⁵, as will be readily understood by reference to Figs. 2 and 3. The 70 inner face G⁸ of the connecting bar G⁶ is roughened so as to firmly engage the outer face of the corresponding side piece F or F'. The rods G⁵ extend through slots G⁹ in the connecting bar G⁶ to allow of using 75 the clamp on side pieces D, F and D', F' of different width. By the arrangement described, the extension side pieces F and F' can be securely clamped to the main side pieces D and D' of the ladder A or B, so 80 that the ladder is increased in length. 85

The extension side pieces F, F' are provided with removable and adjustable supplementary rungs I to permit the user of the ladder to conveniently reach the main rungs 90 E when going up the ladder. Each supplementary rung I is formed of two telescoping members I' and I² adapted to be fastened together by a set screw I³ (see Figs. 1 and 5). The outer ends of the telescoping 95 members I' and I² terminate in U-shaped heads I⁴, I⁵ adapted to straddle the extension side pieces F and F', as plainly indicated in Figs. 1 and 5. The outer members of the heads I⁴, I⁵ are provided with clamping screws I⁶, I⁷ adapted to engage the outer 100 faces of the extension pieces F and F' while inner members of the heads I⁴, I⁵ engage the inner faces of the side extension side pieces F and F'. The inner members of the heads I⁴, I⁵ are preferably roughened, as indicated at I⁸ so that the heads take firm hold on the extension side pieces whenever the clamping screws I⁶, I⁷ are screwed up to 105 securely hold the rungs in position on the extension side pieces F and F'. By making the rungs extensible they can be readily 110

- fitted to extension side pieces F and F' spaced a greater or less distance apart, and the rungs I can be adjusted up or down on the said extension side pieces to space the auxiliary rungs I approximately the same distance apart as the fixed rungs E, and to space the uppermost auxiliary rung I the desired distance apart from the lowermost fixed rung E.
10. It will be noticed that a ladder provided with the extension device shown and described is a true extension ladder in that it has side pieces as well as rungs I the same as the regular ladder.
15. When the extension device is not to be used it can be readily detached from the ladder A or B by removing the clamps G, and the extension device can be readily packed into a small bundle by disconnecting the auxiliary rungs I from the side pieces F and F'.
- Having thus described our invention, we claim as new and desire to secure by Letters Patent:
25. 1. A ladder, comprising main side pieces, rungs rigidly connecting the said main side pieces with each other, extension side pieces fitting against the outer faces of the said main side pieces, clamps adjustably fastening the said extension side pieces to the said main side pieces each clamp having L-shaped members slidably mounted one on the other to fit side pieces of different width, the clamp members terminating in threaded 30 rods, a connecting bar having slots for the passage of the rods to connect the latter with the connecting bar fitting against the outer face of the corresponding extension side piece, the inner face of the connecting bar being roughened, and nuts screwing on the said rods against the connecting bar.
35. 2. A ladder, comprising main side pieces, rungs rigidly connecting the said main side pieces with each other, extension side pieces fitting against the outer faces of the said main side pieces, clamps adjustably fastening the said extension side pieces to the main side pieces, each clamp having L-shaped members slidably mounted one on the other to fit side pieces of different width, the clamp members terminating in threaded 40 rods, a connecting bar having slots for the passage of the rods to connect the latter with the connecting bar fitting against the outer face of the corresponding extension side piece, the inner face of the connecting bar being roughened, and nuts screwing on the said rods against the connecting bar.

45. 3. A ladder provided with a rung made in telescoping sections, each terminating at its outer end in an integral U-shaped clamping head adapted to straddle a side piece of the ladder, one member of the head fitting against one face of the corresponding side piece, and a clamping screw screwing in the other member against the other face of the 50 said corresponding side piece.

55. In testimony whereof we have signed our names to this specification in the presence of two subscribing witnesses.

PHER EDWARD JOHNSON.
EDWARD ANDERSON.
